UNITED STATES PATENT OFFICE.

CHARLES E. BROOKS, OF MONTREAL, QUEBEC, CANADA, ASSIGNOR TO CANADIAN NATIONAL RAILWAYS, OF MONTREAL, CANADA.

ARTICULATED CAR.

Application filed November 6, 1926. Serial No. 146,710.

This invention relates to new and useful improvements in railway cars, and particularly to cars of the articulated type, and the object of the invention is to provide a car which will be of the oil and electric driven type, and in which the driving unit will be located at one end of the car while means will be provided at each end for controlling the car.

10 Another object is to provide a car of simple construction which will have a comparatively large seating capacity as well as a baggage compartment, lavatory equipment, engine room, and control stations.

15 A further object is to provide an articulated or sectional car, the adjacent ends of which will be supported on a common supporting means of the swivel bogie type.

In my invention I provide a railway car 20 built in two sections mounted on three bogies, the central bogie being so positioned that it supports the adjacent ends of the sections. The engine room is located at one end of one of the sections, the other end of 25 which is provided with seating accommodation for passengers, and between the ends a baggage compartment is formed to prevent or deaden the noise of the working of the engine from annoying or disturbing said 30 passengers. The other section is constructed for passenger accommodation, and communicates with the passenger compartment of the other section by means of a covered-in platform. The engine may be controlled 35 from points positioned at the ends of the car remote from one another.

In the drawings which illustrate my improved type of articulated car;

40 Figure 1 is a part sectional plan of the engine room section of the car.

Figure 2 is a part sectional elevation of the part shown in Figure 1.

Figure 3 is a part sectional plan of the 45 passenger accommodating section of the car.

Figure 4 is an elevation of the part shown in Figure 3.

Referring more particularly to the drawings, 11 designates an articulated car built 50 in two sections 12 and 13, mounted on three bogies 14, 15 and 16, which may be of the railway type driven by motors (not shown). The bogies 14 and 16 support the remote ends of the car while the centre bogie 15 is so positioned that it supports the adjacent 55 ends of the sections of the car. The bogies

may be of any of the well known types used in railway car construction, that is, provided with suitable spring cushioning or shock absorbing means, and suitably attached to the underframing of the car to allow the 60 car to pass easily around curves in the permanent-way, without jarring, or the like.

The section 12 is divided into three portions, 17, 18 and 19, by means of partitions 20 and 21. Portion 17 is the engine room, 65 portion 18 the baggage room, and 19 the passenger compartment. The engine room contains a Diesel or semi-Diesel oil engine 22, coupled through suitable wiring (not shown) to the driving elements on the trucks 70 or bogies. The engine and dynamo or generator are shown diagrammatically in Figure 1. Also secured to and positioned within the engine room, are the water tank 24, the fuel oil tank 25, and the lubricating oil tank 26. The operator of the car controls 75 the movement of the car from one corner 27 of the engine room, and may be isolated therefrom by means of suitable partitioning means 28 provided with a swing door 29 to allow easy access to the engine for inspection and repairs. Within the control station at the engine room end of the car, is a controller 30, for regulating the supply 80 of current from the generator to the driving motors on the trucks or bogies. A hand brake lever 31 and an air brake lever 32, may also be provided, and said controller and brake levers may be positioned in close 85 proximity to the observation window 32 90 formed in the car side. A coupling 34 of the standard railway type may be secured to the end of the car. Doors 35 may be provided in the partition 20 to allow easy 95 access from the engine room to the baggage compartment. A door 36 may be provided in the partition 21 between the baggage room and the passenger compartment of this section of the car. Sliding doors 37 and 38 are provided in the side of the car 100 to allow baggage to be placed within or discharged from the baggage room.

The other section 13 is provided with a plurality of seats 39 for passengers, and at the end of said section, remote from the engine room section, suitable entrance and exit doors and steps 40 are provided leading into a landing platform 41 separated from the passenger compartment by means of the partition 42 which is provided with a hinged 110

- door 43. Between the entrance and exit doors and the extreme end of section 13, at one side thereof, is the control station 44, access to which is made through the doorway 45 in the partition 46 surrounding said station. In the control station is the controlling mechanism comprising a controller 47, a hand brake lever 48, and an air brake control lever 49. A standard coupling 50 is secured in any suitable manner to this end of the car. Headlights 51 and warning bells 52 are provided at each end of the car. Cow-catchers 53 may also be provided at each end of the car so that it may be safely operated from either end of the car and in any direction. The car is also provided with ventilators 54 and windows 55 to provide sufficient light within the various compartments within the car.
- 20 In operation it will be seen that the car can be operated in both directions as provision has been made so that the car may be driven from one end or the other. By making the entrance at one end of the car, the conductor of same can without difficulty, keep a perfect check and control on the passengers. The car is driven from an oil engine driving an electric generator forming a single unit, and said unit is isolated 25 from the compartment for the passengers by means of the baggage space, which prevents the noise of the working of the engine from disturbing the passengers. The car which is of the articulated type is self-contained and means are provided to allow easy access to all parts of the car. A folding door 56 may be provided in the wall of the car communicating with the engine room so that said engine may be quickly and easily dismantled for repairs, inspection, and the like, 30 Lavatory space 57 may also be provided in the car in proximity to the exit door. It has been found in operation that the cost of running a car of this type is comparatively 35 small, and that it can be operated at a moment's notice. By providing couplers at the ends of the car, the same may be coupled to standard carriages or cars used for hauling same, and in this operation it 40 has been found that the cost of operation is very much below the cost of operating a steam driven driving unit for this work.
- Having thus described my invention, what I claim is:
- 55 1. An articulated car built in two sections mounted on three bogies, one of said bogies being positioned between and adapted to support the adjacent ends of the sections, an electric generating unit at one end of one of the sections and car controlling means at the remote ends of the sections.
- 60 2. In an articulated car built in two sections, three supporting bogies, one of which is positioned between the adjacent ends of the sections, an electric generating unit at

one end of one of the sections, a passenger compartment at the outer end of the same section, and a baggage room between the generating unit and the passenger compartment.

70 3. In an articulated car built in two sections, three supporting bogies, one of which is positioned between the adjacent ends of the sections, an electric generating unit in a compartment formed at one end of one of the sections, a passenger compartment at the other end of the same section, a baggage compartment between the generating unit compartment and the passenger compartment of the same section, and controlling stations at the remote ends of each of the sections.

75 4. In an articulated car built in two sections, three supporting bogies, one of which is positioned between and under the adjacent ends of the sections, an electric generating unit in a compartment at one end of one of the sections, said unit comprising an electric generator and an oil engine driving the same, a passenger compartment at the other end of the same section, a baggage compartment between the electric generating compartment and the passenger compartment of the same section, the other section of the car being adapted for passengers only, 80 and isolated controlling stations at the remote ends of the sections.

90 5. In an articulated car built in two sections, three supporting bogies, one of which is positioned between and under the adjacent ends of the sections, an electric generating unit in a compartment at one end of one of the sections, a passenger compartment at the other end of the same section, a baggage compartment between the generating compartment and the passenger compartment, accommodation for passengers in the other section, entrance to the car being positioned at the end of the car remote from the generating compartment, means formed in the car for allowing easy access to all parts of the car, and isolated controlling stations at both ends of the car.

100 6. In an articulated car built in two sections, three supporting bogies, one of which is positioned between and under the adjacent ends of the sections, an electric generating unit comprising an electric generator and an oil driven engine coupled directly thereto, said unit being mounted in a compartment 105 at one end of one of the sections, a passenger compartment at the other end of the same section, a baggage compartment in the same section between the generating compartment and the passenger compartment, a collapsible door in the side of the car and at one end thereof, to allow easy access to the engine for repair and the like, passenger accommodation in the other section, entrance doors at the end 110 of the car remote from the generating unit,

means to allow passageways between the ends of the car and isolated control stations at each end of the car.

7. In an articulated car built in two sections, three supporting bogies, one of which is positioned between the adjacent ends of the sections, an electric generating unit mounted in a compartment formed at one end of one of the sections the other end of which is fitted for passenger accommodation, a baggage compartment between the generating and passenger compartments, folding doors at one end of the sections to allow

easy access to the electric generating unit, which comprises an oil engine coupled to an electric generator, means to accommodate passengers in the other section, entrance doors in this section and at the end thereof, remote from the generating section of the car, means to allow easy access to all parts of the car, and isolated controlling stations at each end of the car.

In witness whereof, I have hereunto set my hand.

CHARLES E. BROOKS.
